UNITED STATES PATENT OFFICE.

EDWARD R. BRODTON, OF WASHINGTON, DISTRICT OF COLUMBIA, ASSIGNOR, BY MESNE ASSIGNMENTS, TO SYPHO-CHEMICAL SPRINKLER CORPORATION, OF NEW YORK, N. Y., A CORPORATION OF NEW YORK.

AUTOMATIC FIRE-EXTINGUISHING APPARATUS.

1,299,548.

Specification of Letters Patent.

Patented Apr. 8, 1919.

Application filed May 23, 1914. Serial No. 840,586.

To all whom it may concern:

Be it known that I, EDWARD R. BRODTON, of Washington, District of Columbia, have invented a certain new and useful Improvement 5 in Automatic Fire-Extinguishing Apparatus, and do hereby declare that the following is a full, clear, and exact description thereof.

My invention relates to fire extinguishing 10 apparatus of the type in which the extinguishing fluid, whether a chemical or water, is automatically discharged upon the fire by the opening of sprinkler heads applied to the pipes of the system, or apparatus when 15 a certain predetermined temperature exists, and the object of my invention is to provide such an apparatus of high efficiency, when set in operation, which will be certain to operate under the conditions intended and 20 which will not accidentally operate, and to these ends my invention consists in the fire extinguishing apparatus constructed substantially as hereinafter specified and claimed.

In the form in which I have embodied my 25 invention, a fire extinguishing fluid is used which is contained in a tank from which pipes run to the various parts of the structure to be protected, and such fluid in the pipes is under an initial pressure, and an expelling, or discharging pressure is supplied 30 by a gas generated, as by a mixture of sulfuric acid and bicarbonate of soda, in another tank, this mixture being automatically effected, and in the accompanying drawings 35 I illustrate such an embodiment of my invention in which drawings—

Figure 1 is a side view with parts broken away with enough of such an apparatus to illustrate the same;

Fig. 1^a is a detail view of the automatic signal device for indicating lowering of pressure:

Fig. 2 is a detail view in section on a larger scale showing the devices of the mixing tank for automatically generating the desired pressure;

Fig. 3 a detail view of the check valve mechanism which controls the pipe connection between the two tanks;

Fig. 4 is a detail view illustrating a different construction of the apparatus in regard to the connections between the two tanks;

Fig. 5 is a detail view of one form of sulfuric acid bottle opening device;

Fig. 6 is a detail view in side elevation of the acid bottle stopper;

Fig. 7 is a detail view in section of the compensating device to take care of the liquid contents of the pipe under changes of temperature affecting the pipes, tank, etc.

Referring to the drawings, 10 indicates the tank, or holder for the fire-extinguishing fluid which may be any desired chemical, from the bottom of which runs a pipe 11 that leads through the building having such branches 12 to the different compartments, or rooms thereof, as may be desired, these branches being provided with sprinkler heads 13. Leading into the top of the tank 10 is a pipe 14, which enters the bottom of an air dome 15, preferably of glass, because of its nonporosity, and rendering visible its interior which is partially filled with the fire-extinguishing fluid. A valved pipe 16 leads from a force pump 17 to the pipe 14, a pressure gage 18 being provided to show the pressure produced by the pump in the tank 10 and the pipe connections leading therefrom, the initial pressure in the system being thus produced.

In pipe 14 there is a check valve 19 for holding the pressure in the tank, and in the pipe leading therefrom. Said check valve is preferably constructed and arranged, as shown in Fig. 3 of the drawing, which illustrates a check valve arrangement hereinafter more fully described, which is provided to prevent back pressure from the tank 10. Connected with the pipe 14 at a point between the check valve 19 and the air dome 15, is a signal operating device 20 which acts upon the reduction of pressure in the air dome 15, and gives warning of such reduction of pressure therein. A similar signal device 22 and bell 23 are associated with pipe 14, so that upon the reduction of pressure in the tank 10 and

the pipes leading therefrom, the bell will be sounded and thereby existence of a fire causing the operation of the system will be made known. As shown clearly in Fig. 1^a, said signal device comprises a diaphragm 62, which upon one side is exposed to pressure in the pipe and on the other side has connected to it a rod 63 which carries a collar, or projection 64 that engages a trigger, or latch device 65, and under normal conditions prevents the release of said trigger and thereby prevents the bell, which is of a well known spring actuated type, from being sounded.

A pipe 24 extends from the top of the tank 10 and connects with a pipe 241 leading through the top of the pressure generating tank 25, and a float valve 240 controls the passage from the tank 25 into the pipe 241. In the pipe 24 is a check valve 26 which prevents back pressure from the tank 10 and which, of course, opens under the excess of pressure from the gas generated in the tank 25. The check valve 26 (and similarly the valve 19) is in a goose neck 27 which enables the provision of a volume of oil 28 to surround the valve, a stratum of water 29 being interposed between the body of oil and the fire extinguishing fluid consisting of a chemical supplied from the tank 10, the stratum of water being necessary to prevent the mingling or mixing of the oil and the chemical which does not mix with the water, nor does the water, of course, mix with the oil. The well known fire extinguisher containing carbon tetra chlorid is such a chemical as I have in contemplation. Hence, the check valve is always in a body of oil and is maintained in a condition for instant operation when the conditions in the use of the apparatus require that the check valve shall open.

Within the pressure-generating tank 25, is suspended a bottle, or container 30 for sulfuric acid, said bottle having to one side of its center of gravity a pivotal support that consists of diametrically opposite inverted hooks 31, which, respectively, engage hooks 32 in the lower end of bars 33 depending from the top of the tank 25. The diametrically opposite position of the hooks 31 is indicated in Fig. 1, but the scale of the drawing is too small to indicate their form, and their shape is clearly shown in Fig. 2. The lower ends of the inverted hooks 31 rest in the bottom of the supporting hooks 32, so that when the bottle is turned it rocks upon the bearings thus provided between the two sets of hooks, and the inverted hooks 31 by their turning moving with the bottle are carried sidewise outward through the open sides of the hook 32, and the bottle falling the inverted hooks 31 will be disengaged from the hooks 32 and the bottle precipitated in the soda solution with

its mouth open, the stopper, or cap 34 having previously been removed. The neck of the bottle is sufficiently weight-ed to cause the bottle to remain inverted when it falls into the soda solution. The stopper 34 on its underside has an annular rib 35 which enters an annular groove in the bottle top, the groove being sufficiently larger than the rib to provide a space for a mercury seal. The stopper 34 is attached to the lower end of a vertical rod, or stem 36 which passes through the top, or cover 37 of the tank 25, and above the latter is connected to one end of a lever 38, which at its other end carries a weight 39. Connected to the lever is a vertical rod that extends upward and has its hooked upper end adapted to engage a latch bolt 41, and when so engaged with the latch bolt the lever is held in a position in which the bottle is closed by the stopper 34, while, when the latch bolt 41 is withdrawn from the hooked end of the lever-supporting rod 40, the lever will fall and thus lift the stopper 34 from the bottle, opening the latter and freeing it so that it may revolve from the force of gravity and be precipitated into the tank, thus causing the mixture of the sulfuric acid and the soda solution for the generation of the pressure within the tank 25. The descent of the weighted part of the lever 38 is limited by a vertical bar 42 having a hooked lower end adapted to catch the descending lever, dotted lines in Fig. 1 showing this position of the parts, while, when it is desired to have the weighted portion of the lever to descend further it is lifted out of engagement with the hook of the supporting bar 42, this position also being shown in dotted lines in Fig. 1, and being desirable when access to the tank 25 through the top is desired. The lever 38 is pivoted to some convenient point, such for example, as shown best in Figs. 1 and 2, to a pivot supported from a contiguous pipe. In Fig. 5, another means of pivoting the lever 38 is shown.

The latch bolt 41 is connected to a diaphragm device 43 having a spring tendency to move the latch bolt 41 in the direction to release the lever-holding rod 40, and such tendency is opposed by the pressure within the tank 10 and the pipes leading therefrom through a branch pipe 44 which connects the tank outlet pipe 11, and the pipe 49 leading from the pressure tank 25. Thus, on the reduction of pressure in the pipes leading from the tank 10 throughout the structure, the bolt 41 will be moved to release the lever 38 to bring about the mixing of the sulfuric acid and the soda solution. In order to make the movement of the latch bolt 41 positive and certain, I connect with it a weighted lever 45 which has a pinion 46

that meshes with a rack 47 on the latch bolt, the lever 45 normally leaning from, or being out of a vertical position so that it is always exerting a downward tendency, which is in 5 the direction to move the bolt 41 to release the lever 38 that controls the mixing of the two chemicals for the generation of pressure in the tank 25.

In order to avoid the use of a stuffing box 10 and to secure a tighter joint than packing would afford where a stem 36 passes through the cover of the pressure tank 25, I attach the stem 36 to a diaphragm 46 in a chamber 47 that is screwed to the cover 37, the diaphragm 46 allowing by its vibration enough movement for the lifting of the stopper 34 by the action of the lever 38.

Supplementing the use of a chemical fire extinguisher, I provide means for using 20 water taken from a suitable source, as for example the city supply, for this purpose, leading therefrom a pipe 48 to the bottom of the pressure tank 25. Thus water may enter the tank 25 and pass therefrom 25 through the pipe 241 leading from the tank 25. To avoid the passage of water through the chemical holding tank 10, the branch 44 which connects the pipes 11 and 24 may be used, a three-way valve 50 being provided at 30 the junction of the pipe 11 and the pipe 44, and a three-way valve 51 being provided at the junction of the pipe 24 and the pipe 44, and both valves having crank handles that are connected by a pitman 52 to which is connected a common-operating handle 53. The 35 passage of water through the pipe 48 is controlled by a cock 54 which is adapted to be opened by a weighted lever 55 that is normally held in the position to keep the cock 40 54 closed by a hook-rod latch-bolt connection operated by a diaphragm in a casing 56 similar to that for the lever 38. A stop cock 57 is provided at the junction of the 45 pipes 241 and 49 so as to enable the pipe 49 to be opened or closed to the passage of liquid through it. When it is closed and at the same time water is admitted through the pipe 48 to the tank 25, the air in the latter (which will then contain no soda solution) is compressed and thus ejecting pressure for the fire extinguishing chemical in 50 the tank 10 is provided independently of the mixture of the sulfuric acid and the soda solution.

55 The stop cock 57 is a three-way valve which so controls the flow through the pipes 241 and 49 that when gas is passing from the tank 25 into the pipe 241 there is no passage through the pipe 49, and when the stop cock 60 or valve 57 is placed in position to open the passage through the pipe 49, which is the condition when it is desired to discharge the soda solution on to the fire there can be no flow from the tank 25 into the pipe 241;

and when the soda solution is thus used the 65 three-way valves 51 and 50 switch off the tank 10 so that the soda solution does not pass through the latter, but passes from the pipe 24 through the branch 44 to the main supply pipe 11. When water is to be supplied to the fire, the float valve 240 is removed, or rendered inactive so that water will pass from the tank 25 through the pipe 241 in which case, of course, the three-way 70 cock 57 is turned to cut off the passage 75 through the pipe 49, while allowing passage from the tank 25 into the pipe 241, the water being passed preferably through the branch or by-pass 44 without passing through the tank 10.

80 Liquids are practically incompressible. The tanks and pipes, however, are affected by changes in temperature so that by shrinkage the space for the liquid is reduced, while the quantity of liquid remains the 85 same. To prevent this condition bursting the tanks, or pipes, I provide, as in the pipes 12, at suitable points, expansion chambers 58 having flexible walls that yield under a certain predetermined maximum pressure 90 and resume their normal condition upon the lowering of the pressure from that maximum.

95 Preferably a diaphragm operated alarm 59 is connected with the pipes 12 so that when a sprinkler head goes off on account of a fire the alarm will be automatically sounded. To limit this action to the particular room, or section of the building involved, I run the sprinkler head pipes 12 in different directions from the supply pipe 11 and in each pipe 12 at one side of the supply pipe 11, I place a check valve 60 which prevents the reduction of pressure in one pipe 12 from affecting another pipe 12 where no 100 105 sprinkler head is blown off.

110 It is convenient to attach a hose 61 to the supply pipe 11 so that the extinguishing fluid may be applied directly to an outbreak of fire at localized points.

Instead of the arrangement of the lever 38, the diaphragm 43 and the connections between the lever and the bottle stopper 34 which appears in Fig. 1, I may use that appearing in Fig. 4, where a diaphragm in 115 casing 430 corresponding to the diaphragm 43 is connected directly to the lever 381, so that the latch bolt 41 and the weighted lever 45 are dispensed with, the lever 381 being connected to the stopper stem 36, as in the 120 construction shown in Fig. 1.

By the construction shown in Fig. 5, the check valve 26 may be discarded and in place thereof a stop cock 260 used to which the lever 380 is attached and which forms its 125 pivotal support in which case the pipe communication between the tanks 10 and 25 is positively opened by the dropping of the

weighted end of the lever 380, when it is released.

Supplementing the audible signal consisting of the bell 23 which announces the reduction of pressure in the system by the opening of the sprinkler head, or leakage, I provide as best shown in Fig. 1^a a visual signal that consists of a target 79 carried by a lever 80 pivoted to the casing 22 which has a finger 81 in the path of a lug 82 on the diaphragm stem 83 so that when the latter is moved in the direction to cause the operation of the bell the target 79 will be thrown into indicating position. Thus, if no one should happen to be present at the time the bell is sounded, upon his return to the apparatus at this point, the position of the target would indicate what had happened. This target is especially useful in giving notice of leakage.

My use of diaphragms is of great value and importance because I thereby render the apparatus sensitive and certain to act, because there are no sliding parts which are apt to stick together and thus fail to act at the critical time.

Surrounding the stem of the stopper 34 is a coil spring 75 which acts to press the stopper upon the mouth of the bottle, a loose connection being provided between the stopper 30 and its stem to permit slight movement of the stopper. This loose connection is formed by a pin 76 passing diametrically through the stem and through vertically elongated openings or slots in the stopper 34. The upper end of the spring reacts against a member on the rod.

The mercury seal for the sulfuric acid bottle or tank effects the hermetic sealing of the bottle so that the strength of the acid is not impaired since no fumes can pass the seal.

To simplify the form of the apparatus, the fire extinguishing fluid need not be contained in a holder, or receptacle in the form of a tank, but the system of piping may contain enough, in which case a tank, such as tank 10, may be discarded. This and other changes may be made, so that it is to be understood that I do not limit myself only to the details of construction which I have shown in the drawings and described as one embodiment of my invention.

Having thus described my invention what I claim is—

1. In a fire extinguishing system, the combination of a source of supply of an extinguishing fluid, a discharge pipe leading therefrom that has an outlet, the contents of said pipe consisting of said fluid being kept under a pressure tending to cause the efflux thereof from the pipe, means to normally hold the pipe outlet closed against such efflux, a pair of tanks, or holders for separately holding the chemicals, which when brought together generate a pressure-pro-

ducing gas, one of said holders being contained within the other and having a normally closed discharge orifice, a pivotal support for said inner holder, a stopper for said orifice acting when in the orifice to prevent the turning of the holder, an element connected with the stopper adapted to remove the same from the orifice to uncover the latter and to leave the holder having the stopper free to turn, and means normally holding said element from movement actuated when the pressure in the discharge pipe is reduced by the opening of its outlet. 65

2. A fire extinguishing system comprising a pair of tanks or holders for separately holding chemicals which when brought together generate a gas, one of said tanks being pivotally mounted within the other and having an orifice, a stopper normally closing said orifice, a lever, a connection between the lever and the stopper by which the movement of the lever in either direction is transmitted to the stopper, said connection permitting limited independent movement of stopper and lever, means to move the lever in the direction to lift the stopper 90 from the orifice, and automatic, heat-operated means to control the operation of said lever moving means. 80

3. A fire extinguishing system, comprising a tank for a chemical extinguisher, a heat-operable outlet, a pipe to the latter from said tank, means for the generation of pressure including a tank, a pipe connecting the two tanks, a valved by-pass about said chemical extinguisher tank connecting the 100 two pipes, and a pipe from a source of supply of extinguisher leading into the tank of the pressure-generating means. 95

4. A fire extinguishing system, comprising a tank for a chemical extinguisher, a heat-operable outlet, a pipe to the latter from said tank, means for the generation of pressure including a tank, a pipe connecting the two tanks, a valved by-pass about said chemical extinguisher tank connecting the 110 two pipes, and a pipe from a source of supply of extinguisher leading into the tank of the pressure-generating means, and means normally preventing flow through said last named pipe acting to open the 115 same when said outlet opens. 105

5. A fire extinguishing apparatus, comprising in combination inner and outer tanks, a pivotal support for the inner tank, and means comprising separable members 120 loosely mounting the inner tank upon said pivotal support to one side of the center of gravity whereby when said inner tank turns upon its pivotal support it disengages therefrom. 125

6. A fire extinguishing apparatus, comprising in combination inner and outer tanks, a pivotal support for the inner tank,

and means comprising interengaging separable hooks loosely mounting the inner tank upon said pivotal support to one side of the center of gravity whereby when said 5 inner tank turns upon its pivotal support it disengages therefrom.

In testimony that I claim the foregoing I have hereunto set my hand.

EDWARD R. BRODTON.
